CLAIM

The ornamental design for a pet mattress for pet separator and protection device, as shown and described.

DESCRIPTION

FIG. 1 is a front perspective view of a pet mattress for pet separator and protection device;

FIG. 2 is a front view of the pet mattress for pet separator and protection device;

FIG. 3 is a rear view of the pet mattress for pet separator and protection device;

FIG. 4 is a top view of the pet mattress for pet separator and protection device;

FIG. 5 is a bottom view of the pet mattress for pet separator and protection device;

FIG. 6 is a first side view of the pet mattress for pet separator and protection device;

FIG. 7 is a second side view of the pet mattress for pet separator and protection device;

FIG. 8 is a perspective view of the pet mattress for pet separator and protection device located on a pet separator and protection device; and,

FIG. 9 is a perspective view of the pet mattress for pet separator and protection device attached to a pet separator and protection device which is located on a bed, a dog laying on the pet mattress for pet separator and protection device, and a person on the bed.

The broken lines in FIGS. 8 depicting a pet separator and protection device, represent environmental subject matter and form no part of the claimed design. The broken lines in FIG. 9 depicting a bed, a pet separator and protection device, a dog, and a person, represent environmental subject matter and form no part of the claimed design.
